UNITED STATES PATENT OFFICE.

JACK KATZ, OF NEW YORK, N. Y.

DESIGN FOR A CLOCK CASE.

Application filed August 2, 1927. Serial No. 22,976. Term of patent 3½ years.

To all whom it may concern:

Be it known that I, JACK KATZ, a citizen of the United States, and residing at New York, in the county of New York and State of New York, have invented a new, original, and ornamental Design for a Clock Case, of which the following is a specification, reference being had to the accompanying drawings, forming part hereof.

Fig. 1 is a side elevation of a clock case showing my new design, and Fig. 2 is a rear view.

I claim:

The ornamental design for a clock case as shown.
